UNITED STATES PATENT OFFICE

JULIEN MAHÉ, OF PARIS, FRANCE

CARBURETOR

Application filed March 15, 1928, Serial No. 262,000, and in France March 16, 1927.

The object of my invention is to provide an improvement in explosion engine carburetors.

Said improvement contemplates to facilitate motor starting and to save fuel during normal operation and consists in fitting the carburetor, whatever the type thereof, with one or several tubulures opening into free air above the level of the petrol (gasoline) contained in the float chamber and communicating with the spray nozzle or nozzles and, consequently, with the said chamber. In ordinary conditions, therefore, petrol (gasoline) will rise in those tubulures up to a height corresponding to its level in the chamber, thereby forming an additional petrol (gasoline) charge which, on starting, is, through the sucking action of the engine, immediately carburized and forms a very rich and highly homogeneous mixture, well calculated to facilitate the starting of the engine. When the tubulure or tubulures are sucked empty of their petrol (gasoline) charge, they serve as supplementary air intakes, thus doing duty as automatic fuel-savers.

The single figure in the drawing appended hereto illustrates, as an example, an embodiment of the device, the main characteristics of which have just been hereinabove set forth. A denotes the float chamber communicating through conduit B with the slow-run C and normal run D spray-nozzles. Below said nozzles are secured, at E and F, tubulures G and G' open to atmosphere at H, H' at a level above the top of chamber A.

As explained above the gasoline will rise in tubulures G and G' to the level corresponding to its height in the float chamber A. When the engine is started the fuel will be supplied thereto not only from the float chamber but also from the additional reserve in tubes G and G', so that due to the rich mixture prompt starting of the engine will occur. When the content of tubes G and G' is used up, these tubes will act from that time on, and while the engine is running, as supplemental air inlets, thus rendering the mixture leaner and causing a saving in the fuel consumption.

Of course, the arrangement of those tubu-

lures may be varied according to the type of carburetor and the fitting up means will have to be suited to each case.

Having now particularly ascertained and described the nature of my said invention as well as the manner in which the same is to be performed, I declare that what I claim is:

1. The combination with a carburetor having a float chamber an idling speed nozzle and a normal speed nozzle for supplying fuel to an internal combustion engine, of supplemental conduit means between the float chamber and each of said nozzles, said conduit means having a permanent connection with the fuel at a point considerably below the level of the fuel in the float chamber and also a permanent connection with the atmosphere at a single point considerably above the level of the fuel in the float chamber.

2. The combination with a carburetor having a float chamber and an idling speed nozzle and a normal speed nozzle for supplying fuel to an internal combustion engine, of additional conduit means between the float chamber and each of said nozzles, said conduit means consisting of a plurality of tubes, each having a portion substantially below the level of the gasoline in the float chamber and another portion extending substantially above the level of the gasoline in the float chamber, and communicating with the atmosphere at one point only.

3. The combination set forth in claim 2, wherein the tubes lie wholly outside of the carburetor and have a detachable connection therewith.

In testimony whereof I affix my signature.

JULIEN MAHÉ.
